(57) **CLAIM**

The ornamental design for a tire carrier gate, as shown and described.

DESCRIPTION

FIG. 1 is a rear side perspective view of a tire carrier gate, in use condition showing my new design;

FIG. 2 is a right side elevation view thereof;

FIG. 3 is a left side elevation view thereof;

FIG. 4 is a top plan view thereof;

FIG. 5 is a bottom plan view thereof;

FIG. 6 is a rear elevation view thereof; and,

FIG. 7 is a front elevation view thereof.

The dash-dot even broken lines illustrate and surround portions of the tire carrier gate that form no part of the claimed design. The dash-dot-dot broken lines shown in the drawings illustrate vehicle environmental subject matter which forms no part of the claimed design.
